FOUNTAIN PEN

Filed Dec. 23, 1936

INVENTOR

Frank M. Ashley

19, then unscrewing the handle from the barrel and reciprocating the piston-rod.

On the outward stroke of the piston-rod, the tube 20 slides thru the piston 22 until the abutment-ring contacts and moves it to the upper end of the chamber 38.

This movement causes all of the air or liquid in chamber 38 to flow either thru the ports 24 of the piston into the feed-chamber 15, or a part thereof thru the passages 28 and tube 20 to the atmosphere.

On the inward stroke, the valve 28' closes the ports 24 in the piston, and ink flows thru the passage 19, tube 20 and passages 28 into the chamber 38 and fills the same.

On the next outward stroke of the piston-rod, ink passes from the chamber 38 thru the piston into chamber 15 and completely fills it, and the next inward stroke again draws ink thru the tube into chamber 38 while the surplus ink in the feed-chamber 15 is discharged therefrom thru the ink-duct in the feed-plug back into the bottle containing the ink supply, leaving both chambers of the pen full of ink, and the valve in its closed position, after which the handle is rotated to cause the threads 35 and 36 to engage and rest the co-acting parts of the pen in normal positions, as illustrated in Figure 1, and causing the tube to overlap and close the passage 19 to prevent ingress of air to the chamber 38 or leakage therefrom thru said tube.

When the feed-chamber is empty or partly empty, it may be filled by unscrewing the handle a turn or two, thus opening the valve to permit ink to flow from the chamber 38 to the feed chamber 15 thru the ports 24, and thereafter closing said ports by screwing the handle to its normal position of rest.

The pen may be cleaned thoroughly by pumping clean water thru the chambers, as in the act of filling the pen with ink, as will be readily understood.

Having thus described my invention, I claim as new:

45 1. A fountain pen comprising a barrel having a reservoir for ink therein, a feed-plug having a feed duct in open communication with said reservoir and having a central bore leading from the reservoir to the atmosphere, a piston in said reservoir having a central opening and an opening at one side thereof, a closure for the rear end of said reservoir, a piston-rod extending therethru, a valve carried by said piston-rod to control the flow of ink thru said piston, a tube connected 50 to said piston-rod and extending thru said cen-

tral opening in the piston and into said central bore in the feed-plug, said tube being in open communication with the reservoir between the piston and said closure for the rear end of the reservoir; the construction being such that the movement of the piston-rod in one direction will open the valve and move the piston toward the rear end of the reservoir, and the movement thereof in the opposite direction will close said valve and move the piston in the opposite direction in the act of filling the reservoir with ink. 5

2. The construction defined in claim 1, together with; and means for closing the said tube when in its normal position of rest.

3. A fountain pen comprising a barrel having a reservoir for ink therein, a feed-plug having a feed-duct in open communication with said reservoir and having a central bore leading from the reservoir to the atmosphere, a piston in said reservoir located between its ends to provide two chambers, a closure for the rear end of said reservoir, a piston-rod extending therethru, a tube connected to said piston-rod and extending thru said piston and into said central bore in the feed-plug; said piston having a passage leading therethru, a valve carried by the piston-rod for controlling said passage whereby the chambers may be in open or closed relation to each other; said construction being such that the movement of the piston-rod in alternate directions will act 30 to draw ink into said reservoir thru said tube to fill one of said chambers and permit ink to flow therefrom to the other chamber thru the valve controlled passage.

4. A fountain pen comprising a barrel having a reservoir for ink therein, a feed-plug having a feed-duct in open communication with said reservoir and having a bore leading from the reservoir to the atmosphere, a piston in said reservoir located between its ends to provide two chambers, 40 a closure for the rear end of said reservoir, a piston-rod comprising a tube which extends into said bore in the feed-plug; said piston having a central aperture thru which the piston-rod extends, a valve carried by the piston-rod for closing 45 said aperture when the piston-rod is moved in one direction and for opening the aperture when moved in the opposite direction, said valve serving to divide the reservoir into two closed chambers; said construction being such that the movement 50 of the piston-rod in alternate directions will act to draw ink into said reservoir thru said tubular portion of the piston-rod to fill said chambers.
